UNITED STATES PATENT OFFICE.

ALBERT E. CLARKE, OF DES PLAINES, ILLINOIS, ASSIGNOR TO BENJAMIN ELECTRIC MANUFACTURING COMPANY, OF CHICAGO, ILLINOIS, A CORPORATION OF ILLINOIS.

DESIGN FOR AN ENAMELED-METAL TABLE TOP.

Application filed November 21, 1921. Serial No. 516,888. Term of patent 14 years.

To all whom it may concern:

Be it known that I, ALBERT E. CLARKE, a citizen of the United States, residing at Des Plaines, in the county of Cook and State of Illinois, have invented a new, original, and ornamental Design for Enameled-Metal Table Tops, of which the following is a specification, reference being had to the accompanying drawing, forming a part thereof.

In the drawing:

Fig. 1 is a top plan view of an enameled metal table top, showing my design; and

Fig. 2 is a fragmentary perspective view showing the edge portion of the table top.

I claim:

The ornamental design for an enameled metal table top, as shown.

In witness whereof, I have hereunto subscribed my name.

ALBERT E. CLARKE.
